POLE TOP INSULATOR HOLDING BRACKET

James D. Coon, Portland, Oreg., assignor to Western
Power Products, Inc., Portland, Oreg.

Filed June 29, 1973, Ser. No. 375,040

Term of patent 14 years

Int. Cl. D8—08

U.S. Cl. D8—234

FIG. 1 is a side elevational view of a pole top insulator holding bracket showing my new design;

FIG. 2 is a rear elevational view of the bracket, taken on the line 2—2 of FIG. 1;

FIG. 3 is a front elevational view of the bracket, taken on the line 3—3 of FIG. 1;

FIG. 4 is an end view taken from the left side of FIG. 2;

FIG. 5 is an end view taken from the right side of FIG. 2;

FIG. 6 is a side elevational view of a slightly modified design for the pole top insulator holding bracket;

FIG. 7 is a rear elevational view of the bracket of FIG. 6, taken on the line 7—7 of FIG. 6;

FIG. 8 is a front elevational view of the bracket of FIG. 6 taken on the line 8—8 of FIG. 6;

FIG. 9 is an end view taken from the left side of FIG. 7; and

FIG. 10 is an end view taken from the right side of FIG. 7.

I claim:

The ornamental design for a pole top insulator holding bracket, as shown and described.
